DISPLAY STAND

Benjamin Gittleman, Providence, R. I.

Application January 13, 1931. Serial No. 508,488

14 Claims. (Cl. 206—79)

My invention relates to improvements in display devices.

An object of my invention is to provide a duplex display stand which may be used for various purposes comprising a base and side walls projecting upwardly from said base to an apex and each side wall being arranged to display identical subject matter so that the display stand will present substantially the same appearance whether it is viewed from the front or the rear, thus providing a duplex display stand which may be stood on any high object such as a counter and from which the display matter will be equally visible from either side.

15 A further object of my invention is to provide such a display stand having a plurality of detachable packages of merchandise detachably securable thereto, preferably an equal number of said detachable packages on each side providing a dispensing as well as a display device adapted to display an equal number of packages and preferably advertising matter relative thereto from each side thereof.

Further advantages of my invention relate to 25 the detailed construction of the display stand itself and the packages themselves. I preferably so construct my duplex display stand that it is constructed from a single sheet of material and it is preferably provided with a central portion 30 printed on each side with identical advertising matter. Said single sheet of material is bent into duplex sides substantially near the center thereof along a flexible line, preferably where a display stand having a central portion is provided, 35 near each side thereof. In order that the central portions displaying the advertising matter may be more readily visible from each side the central portion is preferably cut out from one side into the other side thereof for a distance and said opposite side also preferably cut down so that said 40 central portion may project upwardly from one side thereof and display equally said identical printing advertising matter on each side thereof when the sides are stood up on end. I also preferably provide similar advertising matter on other 45 exposed portions of each side of said card.

Further features of my invention relate to the specific construction of spacing base I employ for the easel or duplex display stand of my invention 50 by providing a base which will remain rigid when set and which may be readily unfolded so that the sides of the duplex display stand may be compressed for shipping purposes.

55 A further object of my invention relates to the specific construction of the improved pack-

ages which I dispense preferably from each side of the display stand and in combination therewith the specific structure of the means I provide on said display stand for detachably securing said packages thereto. I provide a structure including preferably a plurality of packages preferably of small articles such as shoe laces, shoe accessories, etc., which may be readily attached or detached to the side of the display stand or card and which may also if desired be readily packed 60 into the packages or removed therefrom as desired.

A further feature of my invention relates to the improved type of package I preferably employ which, if desired, may be readily attached or detached to a display card as well as to the preferred type of display stand I preferably employ.

These and such other objects of my invention as may hereinafter appear will be best understood from a description of an embodiment thereof, such as is shown in the accompanying drawings.

In the drawings, Fig. 1 is a side elevation showing one side of a display stand constructed in accordance with the teachings of my invention.

Fig. 2 is a side elevation of the opposite side thereof.

Fig. 3 is an end elevation thereof.

Fig. 4 is a detailed sectional view showing the specific type of means I preferably employ for detachably securing my improved type of package to a side of a display card or stand.

Fig. 5 is a plan view of the single sheet of material from which both sides of my improved duplex display stand may be readily constructed.

Fig. 6 is a perspective view of the improved type of shoe lace package I preferably employ.

Fig. 7 is a perspective view of my improved package shown in Fig. 6 illustrating how a pair of shoe laces may be readily packed therein.

In the drawings, wherein like characters of reference generally indicate like parts throughout, 10 generally indicates a display stand constructed in accordance with the teachings of my invention.

My improved display stand 10 includes a duplex display card 12 such as is illustrated in Fig. 5 as formed from a single sheet of material.

Said display card 12 has a central portion 14 preferably printed on each side thereof as at 15 and 15' as shown in Figs. 1 and 2 with identical advertising matter and is preferably bent into two duplex sides 16 and 16' at substantially the center thereof along a flexible line 18 namely, in the preferred embodiment the flexible lines 18 and 18' near each side thereof.

The central printed portion 14 is cut out from the side 16 into the other side 16^a for a distance and said side 16^a is preferably additionally cut down as at 20 (see Figs. 2 and 5) for a distance 5 to permit said central portion 14 to project upwardly from one side and equally display said printed advertising matter on each side thereof, when the sides 16 and 16^a are stood up on end.

I also provide in combination, with said display card thus formed into the sides as explained a spacing base 22 for said display stand comprising a piece of relatively stiff material 24 having the ends thereof suitably secured to the inner lower ends of said sides 16 and 16^a such as by 10 the paste 26 which secures the tabs 28 upstanding therefrom to said sides. Said portion 24 is preferably flexible centrally as along the line 30 for infolding purposes. I also provide as a spacing member for said base a relatively stiff tab 32 15 of a length corresponding to the desired spacing between said sides projecting inwardly from one side of said stiff material 24 adapted to swing upwardly between said sides when said sides are compressed for shipping purposes as shown in dotted lines in Fig. 3 and adapted to project 20 horizontally over said material to abut the opposite side 16^a to form a base and space said sides apart thus forming in used position as shown in full lines in Fig. 3 a duplex display stand comprising the base 24, the side walls 16^a and 16 projecting upwardly from said base to an apex, the side 16 thereof having a portion 14 projecting centrally upwardly therefrom, having 25 duplicate display matter on each side thereof and the other side having a cooperating cut out portion 20 whereby said display matter is equally visible on both sides. It is obvious that when it is desired to knock down my improved easel or display stand for shipping purposes that the spacing portion 32 is lifted upwardly adjacent to the side 16 and that the base 24 may be compressed between said sides 16 and 16^a along the flexible line 30 to form a substantially flat device for 30 shipping purposes.

I preferably, however, employ in combination with my improved display stand or if desired with a display card, a plurality of packages adapted to be detachably secured thereto and for this purpose I provide the plurality of sets 35 of spaced opposite disposed preferably horizontal prongs projecting outwardly from said sides 16 and 16^a, thus formed by being cut out from said base, for a purpose to be described one prong 38 of each set 36 being preferably longer than the opposite prong 40 of said set. These sets of prongs form means for detachably securing my improved packages to my improved duplex display stand or to any type of a card.

I provide a plurality of oblong boxes 42 having open ends 44 each adapted to receive one of each sets of prongs 36 to mount each respective box on a side of said display stand or card and my improved package is preferably provided with an elongated longitudinally disposed dispensing opening in the top wall thereof.

My invention is particularly adapted for holding in each package thereof a number of frangible articles and is particularly adapted for holding a number of folded and banded packages 48 of shoe laces 50, each shoe lace package consisting of a plurality of shoe laces 50 such as a pair folded and banded together by the band 52 in the manner common to the art. Said packages 48 are packed into the box 42 side by side and extend in the same direction as the long

axis of the dispensing opening 46 of the box, the ends of the shoe lace packages 48 thus extending beyond the ends of the dispensing opening 46 in the top wall 54 of said box.

As stated each banded package preferably includes a pair of shoe laces and in the embodiment shown each box 42 contains two pairs or two packages of a pair each of banded shoe laces. 80

The box shown as 42 provides a very desirable medium for packing the shoe lace packages 85 therein. As shown in Fig. 7 two of such packages 48 each containing a pair of shoe laces each provided with a band 52 on which advertising matter may be displayed are squeezed side by side together in the hand. One end of said combined packages 48 is then inserted through the elongated opening 46 as shown in Fig. 7 until it projects through the opening 44 in one end of said box. It is thus obvious that the opposite end of 90 said package may then be readily compressed through the opening 46 into the box and the shoe lace packages slid over until they are entirely contained within the box 42 and so that the ends thereof may extend beyond the ends of the dispensing opening 46 in the cover 54 but are contained within the box inwardly of the open ends 44 and 44' thereof. If desired the shoe lace packages may be individually removed from the boxes 42 either by grasping them at their centers 95 and lifting them directly out of the opening 46 causing the packages of shoe laces to flex and the ends to be released from under the ends of the cover without removing the packages from the display stand or card or the shoe lace packages 100 48 may be readily pushed out through an end 44 and 44' of said box with or without removal from the display stand or card.

To attach a package to the display stand or box as illustrated in Fig. 4 it is merely necessary to slide the box 42 so that the longer prong 38 115 where employed may slide through the open end 44' of said box underneath the shoe lace packages 48 and the opposite prong 40 may be readily inserted in the opposite end 44 of the box either by pushing it out forwardly from the card 16 or by 120 pushing the whole box 42 over underneath the prong 38 so that the prong 40 may be slid into position underneath the shoe lace package at the open end 44 of said box 42 and it is obvious that the packages may be similarly detached from the 125 display card or stand in the opposite fashion.

It is thus obvious that I have provided a novel type of package for small articles such as shoe laces which is so constructed as to be particularly adapted to be attached to or detached from a 130 display or dispensing card or stand particularly of a duplex type and particularly adapted for use in displaying said detachable packages. It is also apparent that I have provided a duplex display stand having such novel features of its 135 own, which is particularly useful in combination with said packages as a dispensing stand therefor.

It is understood that my invention is not limited to specific embodiment shown and that various deviations may be made therefrom without departing from the spirit and scope of the appended claims.

What I claim is:

1. A duplex display stand comprising, in combination, a duplex display card formed from a single sheet of material having a central portion printed on each side with identical advertising matter and bent into two duplex sides substantially at the center thereof along a flexible line near each side thereof and having the central 145 150

- printed portion cut out from one side into the other side thereof for a distance and said side cut down to project upwardly from one side and equally display said printed advertising matter 5 on each side thereof when said sides are stood up on end, a plurality of sets of spaced oppositely disposed prongs projecting horizontally outwardly from said sides one prong of each set being substantially longer than the other, similar advertising matter on the exposed portion of each side of said card, a spacing base for the sides of said card comprising a piece of relatively stiff material secured to the inner lower ends of said sides flexible centrally for infolding purposes and 10 a relatively stiff tab of a length corresponding to the desired spacing between said sides projecting inwardly from a side of said stiff material adapted to swing upwardly between said sides when said sides are compressed for shipping purposes and adapted to project horizontally over said material to abut said opposite side to form a base and space said sides apart in set position and a plurality of oblong boxes having open ends each adapted to receive one of said sets of prongs 15 20 25 30 35 40 45 50 55 60 65 70 75
- to mount each respective box on said sides and an elongated longitudinally disposed dispensing opening therein and a number of folded and banded packages of shoe laces, said packages being packed into the box side by side and extending in the same direction as the long axis of the dispensing opening in the cover, the ends of the shoe lace packages extending beyond the ends of the dispensing opening.
2. In combination, a display card having a plurality of sets of spaced oppositely disposed prongs projecting outwardly therefrom and a plurality of boxes having open ends each adapted to receive one of said sets of prongs to mount each respective box on said sides and dispensing opening therein and a number of folded and banded packages of shoe laces, said packages being packed into the box side by side, the ends of the shoe lace packages extending beyond the ends of the dispensing opening.
3. In combination, a display card having a plurality of sets of spaced oppositely disposed prongs projecting outwardly therefrom and a plurality of boxes having open ends each adapted to receive one of said sets of prongs to mount each respective box on said sides.
4. In combination, a display card having a plurality of sets of spaced oppositely disposed prongs projecting outwardly therefrom, one prong of each set being substantially longer than the other and a plurality of boxes having open ends each adapted to receive one of said sets of prongs to mount each respective box on said sides and a dispensing opening therein and a number of folded and banded packages of shoe laces, said packages being packed into the box side by side, the ends of the shoe lace packages extending beyond the ends of the dispensing opening.
5. In combination, a display card having a plurality of sets of spaced oppositely disposed prongs projecting outwardly therefrom, one prong of each set being substantially longer than the other and a plurality of boxes having open ends each adapted to receive one of said sets of prongs to mount each respective box on said sides.
6. A duplex display stand comprising, in combination a duplex display card formed from a single sheet of material having a central portion printed on each side with identical advertising matter and bent into two duplex sides substantially at the center thereof, along a flexible line near each side thereof and having the central printed portion cut out from one side into the other side thereof for a distance and said side cut down to project upwardly from one side and equally display said printed advertising matter on each side thereof when said sides are stood up on end, similar advertising matter on the exposed portion of each side of said card, a spacing base for the sides of said card comprising a piece of relatively stiff material having the ends thereof secured to the inner lower ends of said sides flexible centrally for infolding purposes and a relatively stiff tab of a length corresponding to the desired spacing between said sides projecting inwardly from a side of said stiff material adapted to swing upwardly between said sides when said sides are compressed for shipping purposes and adapted to project horizontally over said material to abut said opposite side to form a base and space said sides apart and a plurality of oblong boxes having open ends each adapted to receive one of said sets of prongs to mount each respective box on said sides and an elongated longitudinally disposed dispensing opening therein and a number of folded and banded packages of shoe laces, said packages being packed into the box side by side and extending in the same direction as the long axis of the dispensing opening in the cover, the ends of the shoe lace packages extending beyond the ends of the dispensing opening.
7. A duplex display stand comprising in combination a duplex display card formed from a single sheet of material and bent into two duplex sides substantially at the center thereof along a flexible line, a plurality of sets of spaced oppositely disposed prongs projecting outwardly from said sides, a spacing base for the sides of said card comprising a piece of relatively stiff material having the ends thereof secured to the inner lower ends of said sides flexible centrally for infolding purposes and a relatively stiff tab of a length corresponding to the desired spacing between said sides projecting inwardly from a side of said stiff material adapted to swing upwardly between said sides when said sides are compressed for shipping purposes and adapted to project horizontally over said material to abut said opposite side to form a base and space said sides apart and a plurality of oblong boxes having open ends each adapted to receive one of said sets of prongs to mount each respective box on said sides and an elongated longitudinally disposed dispensing opening therein and a number of folded and banded packages of shoe laces, said packages being packed into the box side by side and extending in the same direction as the long axis of the dispensing opening in the cover, the ends of the shoe lace packages extending beyond the ends of the dispensing opening.
8. A duplex display stand comprising in combination, a duplex display card formed from a single sheet of material having a central portion printed on each side with identical advertising matter and bent into two duplex sides substantially at the center thereof, along a flexible line near each side thereof and having the central printed portion cut out from one side into the other side thereof for a distance and said side cut down to project upwardly from one side and equally display said printed advertising matter on each side thereof when said sides are stood up on end, similar advertising matter on the exposed portion of each side of said card, a spacing base for the sides of said card comprising a piece of relatively stiff material having the ends thereof secured to the inner lower ends of said sides flexible centrally for infolding purposes and a relatively stiff tab of a length corresponding to the desired spacing between said sides projecting inwardly from a side of said stiff material adapted to swing upwardly between said sides when said sides are compressed for shipping purposes and adapted to project horizontally over said material to abut said opposite side to form a base and space said sides apart and a plurality of oblong boxes having open ends each adapted to receive one of said sets of prongs to mount each respective box on said sides and an elongated longitudinally disposed dispensing opening therein and a number of folded and banded packages of shoe laces, said packages being packed into the box side by side and extending in the same direction as the long axis of the dispensing opening in the cover, the ends of the shoe lace packages extending beyond the ends of the dispensing opening.

- posed portion of each side of said card, and a spacing base for the sides of said card comprising a piece of relatively stiff material having the ends thereof secured to the inner lower ends 5 of said sides flexible centrally for infolding purposes and a relatively stiff integral tab of a length corresponding to the desired spacing between said sides projecting inwardly from a side 10 of said stiff material adapted to swing upwardly between said sides when said sides are compressed for shipping purposes and adapted to project horizontally over said material to abut said opposite side to form a base and space said sides apart. 15 9. A duplex display stand comprising in combination, a duplex display card formed from a single sheet of material having a central portion 20 printed on each side with identical advertising matter and bent into two duplex sides substantially at the center thereof along a flexible line near each side thereof and having the central printed portion cut out from one side into the other side thereof for a distance to project upwardly from one side and equally display said 25 printed advertising matter on each side thereof when said sides are stood up on end, similar advertising matter on the exposed portion of each side of said card, a spacing base for the sides of said card comprising a piece of relatively stiff material having the ends thereof secured to the inner lower ends of said sides flexible centrally for infolding purposes and a relatively stiff tab of a length corresponding to the desired spacing 30 between said sides projecting inwardly from a side of said stiff material adapted to swing upwardly between said sides when said sides are compressed for shipping purposes and adapted to project horizontally over said material to abut said opposite side to form a base and space said 35 sides apart. 40 10. A duplex display stand comprising in combination a duplex display card formed from a single sheet of material having a central portion 45 printed on each side with identical advertising matter and bent into two duplex sides substantially at the center thereof along a flexible line near each side thereof and having the central
- printed portion cut out from one side into the other side thereof for a distance to project upwardly from one side and equally display said printed advertising matter on each side thereof when said sides are stood up on end. 80 11. A triangular duplex display stand, comprising a base, side walls projecting upwardly from said base to an apex, and a similar plurality of packages detachably secured to each side, one side having a portion projecting upwardly therefrom having duplicate display matter on each side thereof relative to said packages and the other side having a cooperating cut out portion, whereby said display matter is equally visible on both sides. 85 12. A triangular duplex display stand, comprising a base, side walls projecting upwardly from said base to an apex, one side having a portion projecting upwardly therefrom having duplicate display matter on each side thereof and the other side having a cooperating cut out portion, whereby said display matter is equally visible on both sides. 90 13. A display card having a set of spaced oppositely disposed prongs projecting outwardly 100 therefrom and boxes having open ends each adapted to receive one of said prongs to mount it thereon and an elongated longitudinally disposed dispensing opening therein and a number of folded and banded packages of shoe laces, 105 said packages being packed into the box side by side and extending in the same direction as the long axis of the dispensing opening in the cover, the ends of the shoe lace package extending beyond the ends of the dispensing opening. 110 14. A display card having a set of spaced oppositely disposed prongs projecting outwardly 115 therefrom and boxes having open ends each adapted to receive one of said prongs to mount it thereon and a dispensing opening therein and 120 a number of folded and banded packages of shoe laces, said packages being packed into the box side by side, the ends of the shoe lace packages extending beyond the ends of the dispensing opening. 125 BENJAMIN GITTLEMAN. 130 135 140 145 150
